SHAPE-RETAINING DEVICE FOR HATS

Ralph L. Knibloe, Sharon, Conn.

Application June 4, 1938, Serial No. 211,759

1 Claim. (Cl. 2-185)

This invention relates to shape-retaining devices for hats, and more particularly to devices adapted for example to retain the shape of the crown portion of hats made of pliable material 5 such as soft felt.

The objects of the invention include the provision of a simple, inexpensive, effective and durable device of the above indicated character which may be easily inserted in the hat. In accordance with this invention such device may be formed for example of a layer of fibrous material so made or treated that it will have a firm rough surface for engaging the interior surface of the hat and thereby preventing displacement 15 of the device. Furthermore, in accordance with this invention, the device may be made of an integral piece of material so formed or treated that it will permanently retain its shape, the shape being preferably such as to provide a semi-rigid backing for the front portions of the walls 20 of the crown of the hat, whereby such portions are retained in a shape adapted to be firmly gripped in one hand to remove the hat without crushing, unduly creasing, or otherwise deforming or damaging the felt and the appearance of 25 the hat.

I am aware that various devices have heretofore been proposed for retaining the shape of felt hats, but such devices so far as I am aware, have not come into practical use to any substantial extent, 30 for the following reasons. It has been proposed, for example, that such devices be formed of a thin sheet of metal or of Celluloid, or the like materials. But if such material is made thin enough 35 to avoid being cumbersome, and stiff enough to be effective, it will crack upon repeated use. Furthermore, such devices of these materials quickly slip out of the desired position within the hat, inasmuch as the metal, Celluloid or the like will 40 slide freely along the surface of materials generally used for hats unless resort is had to the use of pins or the like mechanical retaining means, which in turn will mar the hat, destroy the desired smooth contours thereof, or involve 45 difficulties in affixing the same in position. Also, such devices of sheet metal, Celluloid or the like, soon cause the hat to be sharply creased along the rigid edges of the device, with the result that the outline of the device is made visible from the 50 exterior of the hat, or such edges cut into and soon destroy the felt. Also crown supporting devices and mechanisms of irregular mechanical shapes have been proposed, but so far as I am aware, these have all been such as to either leave 55 the portion of the crown which is grasped by the user in removing the hat, unsupported against crushing or else supported only at irregular intervals by protruding parts which disfigure the smooth contours of the hat after repeated use.

60 Also in some cases attempts have been made to

provide a rigid arcuate backing for the front walls of the crown of the hat, but with such a backing it is substantially impossible for the user to quickly and securely grasp this portion for removing the hat in any convenient or natural manner, since the fingers and thumb will slide off the arcuately supported surface. The present invention serves to overcome in a simple manner all of these disadvantages of such prior devices.

Various further and more specific objects, features and advantages of this invention will clearly appear from the detailed description given below taken in connection with the accompanying drawing which forms a part of this specification 10 and illustrates by way of example a preferred form of the invention. The invention consists in such novel features as may be shown and described in connection with the device herein disclosed.

In the drawing, Fig. 1 illustrates a common form of felt hat, within which a device made in accordance with the invention has been inserted;

Fig. 2 is a rear elevational view of a preferred form of device according to this invention;

Fig. 3 is a top view of the device of Fig. 2;

Fig. 4 is a view similar to Fig. 1, but illustrating the application of the device to a somewhat differently shaped felt hat; and

Fig. 5 is a sectional elevational view taken substantially along the line 5-5 of Fig. 4.

Referring now to the drawing in further detail, the device 10 embodying this invention may, as shown, comprise an integral layer of fibrous material so treated or formed as to have a firm roughened surface which, when applied against the interior surfaces of a felt hat, will firmly engage the latter and thereby prevent any slipping or sliding of the device out of its intended position. The device may comprise an upstanding relatively stiff area 11 for engaging the front and front portions of the side walls of the crown of the hat. The area 11 at its lower edge may be inserted under the inside hat band 13 as shown in Fig. 5, so that when the hat is being worn, the inside hat band will press against the device and retain it firmly against the inside wall of the hat along which the device cannot slip or slide, in view of the roughened character of its surface. The lower edge if desired may be formed with extensions or tabs as at 12 and 13 for extending horizontally at either side, also in the space between the inside hat band and the lower edge of the crown of the hat. These tabs will serve to further prevent the device from tilting or otherwise moving out of position.

As indicated in Figs. 2 and 3, the area 11 may be so formed that its side portions 14 and 15 diverge rearwardly from each other at a substantial angle, thus providing a vertically extend-

ing somewhat V-shaped or shallow channel-shaped form. More specifically, the portions 14 and 15 may be formed with smooth depressions as shown, conforming generally to the positions 5 of the thumb and forefinger of the wearer's hand when grasping the front of the hat in removing the same. While the portions 14 and 15 may diverge to some extent away from the adjacent normally arcuate wall of the hat, and thereby 10 afford a semi-rigid backing which may be easily gripped, yet such portions conform with sufficient closeness to the wall of the hat to prevent any substantial crushing of the front side wall portions of the crown. That is, the resulting V-shape is such that, with slight flexure the front 15 portion of the crown of the hat may be firmly grasped by one hand for removing the hat without danger that the felt will be so flexed or crushed that it will not immediately revert to its proper position when released from the hand. Furthermore, the shallow channel shape of the 20 upstanding portion of the device serves to impart a further degree of rigidity to the device in a vertical direction without requiring that the device be made so stiff as to be uncomfortable to the wearer or disturb the desired contours of the hat. In addition, the V-shape permits a 25 limited resiliency in horizontal directions when the front portion of the hat is grasped in the hand, enabling the hat to be more securely held, but such resiliency causing the front side wall portions to be forced back into normal position 30 as soon as released from the hand.

In the usual felt hat the top front edge of the 35 crown tends to soon become sharply creased, and certain shape-retaining devices heretofore proposed have been formed with a relatively sharp upper edge, tending to cause such creasing and the wearing or cutting of this area to be even 40 more pronounced. In order to avoid this difficulty, I preferably form the upper edge of the device by bending the upper portion 16 thereof rearwardly and downwardly, so as to form a relatively smoothly curved upper edge 17 against 45 which the felt of the hat may be supported without danger of sharp creasing, cutting or wear.

While various types of materials may be used 50 in forming the device, either of one layer or laminated, as above indicated the material should preferably be somewhat resilient although sufficiently stiffened to permanently retain its characteristic shape as above described and with a permanent firm roughened surface. For these 55 purposes I have found that highly satisfactory results may be obtained by using a layer of relatively thick nap flannel treated with a thermoplastic substance such as cellulose acetate or other ester of cellulose. For example, the nap flannel may be impregnated with a solution comprising 20 parts cellulose acetate and 80 parts of a solvent such as denatured alcohol. The layer of material may then be dried when in flat condition, and cut to the desired outline with a die. Thereupon the die-cut article may be 60 placed upon a surface heated to a temperature in the neighborhood of from 180 to 200° F. When the device is thus thoroughly heated, it may be permanently shaped as shown in Figs. 2 and 3 by applying it to a cold metal form of 65 corresponding shape. The device when made of fibrous material thus treated with a thermo-

plastic substance, will satisfactorily retain its shape and stiffness at all temperatures customarily met with in the use of the device. Furthermore, the device will be uninjured by moisture whether due to perspiration or rain. Yet the 5 device will be of a textile character somewhat porous and light in weight, and therefore does not incur any discomfort or inconvenience to the wearer. Hats in which such a device is used maintain their desired original shape even after 10 long use. The presence of the device is in no way evident from the exterior appearance, that is, the outlines of the device are never revealed on the exterior of the felt. With the usual felt hat, upon long continued use, the location of the 15 crease of the crown tends to gradually shift to one side of the middle of the front portion of the hat, thus giving the hat an awkward appearance. I have found that this difficulty is wholly avoided by the use of the above described shallow 20 channel-shaped device.

Various other known fabric-stiffening treatments with other cellulose compounds, such for example as ethyl cellulose or other cellulose ethers or esters, may be substituted for the above 25 described use of cellulose acetate. In some cases instead of using a nap flannel material, one may use an inexpensive form of burlap having a somewhat roughened surface after treatment with the thermoplastic material or the equivalent. 30 If it is desired to use other textile materials such for example as buckram, they may in some cases be stiffened with cornstarch, but in such event a further coating of a water-resistant or water-repellant lacquer is preferably applied, the 35 lacquer also preferably including small rough particles which will impart a roughened character to the surface.

While the invention has been described in detail with respect to certain particular preferred 40 examples which give satisfactory results, it will be understood by those skilled in the art, after understanding the invention, that various changes and modifications may be made without departing from the spirit and scope of the invention, and it is intended, therefore, in the appended claim to cover all such changes and modifications.

What is claimed as new and is desired to be secured by Letters Patent of the United States is: 50

A shape-retaining device for hats having a flexible crown, said device being formed of a layer of fibrous material made relatively stiff with a moisture-resistant thermoplastic substance and having a firm rough surface for preventing displacement with respect to the interior surfaces of the hat, the device including a portion adapted for retention under the inside hat band, and an area for extending upwardly from said portion substantially to the top front inside 60 surface of the crown, the upper part of said area being bent over rearwardly to form a firm rounded upper edge, the side portions respectively of said area being formed with rearward depressions for providing a semi-rigid backing 65 for the front side walls of the crown of the hat, and of such shape that the latter may be firmly gripped in one hand to remove the hat without sharp creasing or crushing.
